Canoga Park, Calif. 91304

Filed Jan. 28, 1974, Ser. No. 437,030

Term of patent 14 years

Int. Cl. D20—03

U.S. Cl. D96—12 R

FIG. 1 is a front perspective view of a cyclically moving advertising sign display for stores embodying my new design;

FIG. 2 is a side elevational view thereof;

FIG. 3 is a side elevational view thereof opposite from the view shown in FIG. 2;

FIG. 4 is a bottom plan view thereof;

FIG. 5 is an enlarged fragmentary top plan view thereof, the display being broken away for convenience of illustration;

FIG. 6 is a rear elevational view thereof;

The uprights are broken away in FIG. 1 to indicate indeterminate length and fragmentarily shown in FIGS. 2, 3 and 6 for convenience of illustration.

I claim:

The ornamental design for a cyclically moving advertising sign display for stores, substantially as shown and described.
